UNITED STATES PATENT OFFICE.

AUSTIN C. EVANS, OF SPRINGFIELD, OHIO.

CHECK-ROWER.

SPECIFICATION forming part of Letters Patent No. 445,397, dated January 27, 1891.

Application filed May 6, 1890. Serial No. 350,810. (No model.)

To all whom it may concern:

Be it known that I, AUSTIN C. EVANS, a citizen of the United States, residing at Springfield, in the county of Clark and State of Ohio, have invented certain new and useful Improvements in Check-Rowers, of which the following is a specification.

My invention relates to check-rowers for corn-planters; and it consists in the various constructions and combinations of parts hereinafter described, and set forth in the claims.

In the accompanying drawings, Figure 1 is an elevation of a check-rower device embodying my invention. Fig. 2 is a plan of the same, only so much of the supporting mechanism being shown as is necessary to a proper understanding of the device. Figs. 3 and 4, respectively, are detail views, in elevation, of some of the operating parts shown in different positions. Figs. 5 to 12, inclusive, are detail views of the various parts, which will be more fully referred to hereinafter. Fig. 13 is a sectional view on the line *x x* in Fig. 2.

Like parts are indicated by similar letters of reference throughout the several views.

In the said drawings, A represents a portion of the corn-planter frame to which my improved device is attached.

B B is the frame of the check-rower device, which supports the operating mechanism thereof. The frame B B is connected to the bar A through the medium of a connecting-plate C, which plate C is provided with two wings C' C², as shown in Figs. 8 and 9. The wing C² is provided with a series of serrations a, adapted to be engaged by a series of similar serrations on a flange or projecting ear B' of the frame B B. This ear or flange B' is provided with an elongated opening B², through which is extended a fastening-bolt a', the fastening-bolt a' being also adapted to pass through the wing C² of the plate C. The wing C' of the plate C is provided with a projecting flange a², adapted to extend over the top of the bar A, the wing C' being arranged at the side of said bar and bolted to the same by suitable fastening-bolts a³. By this construction the frame B B is secured firmly to the bar A of the planter-frame, the longitudinal serrations a in the respective parts B' and C² being adapted to hold the said

frame against any lateral or torsional movement of the same, the elongated opening B², however, being adapted to permit of a longitudinal adjustment of the parts to bring the frame B B in its proper relative position with the bar A to cause the operating-lever to be acted upon at the proper point in the manner hereinafter more fully described.

D is the operating-lever, which is preferably formed in two parts b and b', the upper part b being bifurcated in the usual manner, as shown in Fig. 2, to be engaged by an operating-wire y y, the lower part being formed with an elongated opening b², having in one of the walls thereof a projecting lug or shoulder b³. The elongated opening b² is adapted to receive therein a ratchet-wheel c, arranged on one side of a beveled driving-gear D', the projecting shoulder or lug b³ being adapted, when the operating-lever is in its normal position, as shown in Fig. 4, to engage with the ratchet-teeth of said ratchet-wheel c and turn said wheel as the lever is moved in a forward direction, as indicated by the arrow in Fig. 4, the elongated opening b² being adapted to permit of a backward movement of said lever around said ratchet-wheel and independent thereof. The operating beveled gear D' is also provided on its back with an annular flange c', having stop projections c² arranged at intervals around the periphery thereof, preferably four in number.

Arranged above the annular flange c' is a movable catch c², pivoted at c⁵ to the frame B B. On the lower portion b' of the operating-lever D is a projecting cam-faced lug b⁵, adapted to rest under the movable catch c² and hold it away from the annular flange c', as shown in Figs. 3 and 4, the said cam-faced lug b⁵ being adapted, by reason of its peculiar formation, to pass under the hook-shaped end of the catch c² as the lever is moved in the forward direction, thus releasing said catch and permitting it to drop into the position indicated in dotted lines in Fig. 4, and thus engage the stop projection c² and form a stop for the gear D'.

The operating-gear D' is adapted to turn on a sleeve d, secured firmly to the frame B B by a fastening-bolt d', which passes through said sleeve, one end of said sleeve being adapted to rest against the frame B B and the

other against a washer or collar d^2 , the bolt d' being adapted to pass through said collar or washer, and thus bind the parts all firmly together. The hub of the operating beveled gear D' is made of sufficient length to fit snugly between the collar d^2 and the frame B. The face side of the operating-gear D' is formed at the center or about the hub thereof with a ratchet d^3 , similar in shape and size

and number of teeth to the one c on the opposite side of said gear, the pitch or inclination of said teeth being arranged in the opposite direction from those on said ratchet c . A pivoted pawl d^4 , pivoted to the main frame B B, is adapted to engage said ratchet and hold the gear D' against any backward movement.

Located on the top of the frame B B and adapted to turn in a suitable bearing e thereon is what I will term the "crank-gear" D^2 , which engages with the operating-gear D' . This crank-gear D^2 is preferably formed with an extended hub fitted to the bearing e , and is held in position in its bearing by a collar e' and bolt e^2 . The upper portion or back of the gear is provided with a series of serrations e^3 , which are engaged by similar serrations on a crank-arm e^5 , having a wrist or crank pin e^7 . The crank-arm is provided with an elongated opening e^{11} , through which the bolt e^2 passes. The length of the hub of the gear D^2 being such that when the bolt e^2 is drawn tightly against the collar e' and crank-arm e^5 , the parts are all held firmly together, while the gear D^2 is adapted to turn freely in its bearing e .

The crank or wrist e^7 is connected to the operating-lever E of the planter through the medium of a two-part link-connection E', the parts of the link-connection being preferably formed of a screw-threaded rod f , having a hook-shaped projection f' , adapted to pass through a suitable opening in the operating-lever E and be secured therein by a pin or split key f^2 , a screw-threaded portion f^3 being adapted to engage in an internal screw-threaded hub or sleeve f^5 of the other portion f^7 of said link-connection, the part f^7 being journaled on the crank-pin e^7 , and preferably bent or curved, as shown, to bring the hub or sleeve f^5 from the connecting portion f^7 , so that the screw-threaded part f^3 may be adjusted into said hub f^5 , as desired.

The crank-gear D^2 is preferably provided with just half the number of teeth as are formed in the driving-gear D' , so that each revolution of said driving-gear produces two revolutions of said crank-gear.

As before stated, four stops c^2 are employed on the back of the operating-gear, so that at each forward movement of the lever D the operating-gear D' is turned one-fourth of a revolution, while the crank-gear D^2 is turned one-half of a revolution, or sufficient to produce one stroke of the drop-lever E in one direction.

The check-wire y is adapted to pass around supporting sheaves or pulleys g , g' , and g^2 in the main frame in the usual man-

ner, so that the knots or projections thereon shall engage the operating-lever D. As the machine is advanced, the operating-lever D is thrown by said knots or projections in a forward direction, carrying with it the operating-wheel D', the movable catch c^3 being held away from the stop projection c^2 by the cam-faced projection b^5 , as in the manner before described.

Before the operating-lever reaches the limit of its stroke it passes from under the movable catch c^3 , which being thus released drops down upon the annular flange c' and engages with the stop projection c^2 , thus forming a positive stop for the operating gear and lever. The lever has by this time been sufficiently advanced to permit the check-wire to be released therefrom, after which the lever is turned to its normal position by a spring h , secured at one end to a projection h' on said lever and at the other to an adjustable arm h^2 , secured to the frame B. It will thus be seen, as before stated, that each movement of the lever D produces a complete stroke of the drop-lever E.

It will be seen that as thus described I provide a check-rower attachment which is at once simple, complete, and effective in its operation.

By the arrangement described for attaching the supporting-frame to the main planter-frame the operating-lever may be adjusted forward or back in positive alignment, so that the dropping will always come in check.

By the adjustable two-part link-connection E', as described, and the crank-arm and crank-gear the parts may be adjusted to produce any desired stroke of the dropping-lever.

Having thus described my invention, I claim—

1. The combination, with a supporting-frame and an operating-wheel journaled thereon, of a bifurcated lever having an elongated opening adapted to surround a ratchet on said operating-wheel, and a projecting shoulder in said opening formed integral with the walls of said opening, adapted to engage said ratchet, substantially as specified.

2. The combination, with an operating-wheel having the ratchet-teeth and an annular flange with stop projections thereon, of a bifurcated operating-lever having an elongated opening and an engaging projection in said opening formed integral with the walls thereof, a movable catch adapted to engage with said stop projections, and a cam-faced lug on said lever to hold said catch normally out of engagement with said stop projection, substantially as specified.

3. The combination, with an operating-wheel having oppositely-inclined ratchet-teeth on each side thereof, of a bifurcated lever with an elongated opening adapted to surround one of said ratchets, a projection in one of the walls of said opening to engage said ratchet, stop projections on said wheel, and a pivoted catch adapted to engage said

stop projections, means on said lever for normally holding said movable catch out of engagement with stop projections, and a pivoted pawl adapted to engage with the ratchet 5 on the opposite side of said operating-gear, substantially as specified.

4. The combination, with a check-rower, of a pivoted operating-lever having an elongated opening and engaging projection formed integral with the walls of said opening and adapted to engage with the ratchet on an operating-gear, a crank-gear meshing with said operating-gear, and an adjustable crank-arm attached to said crank-gear, substantially as specified.

5. The combination, with an operating-gear having oppositely-arranged ratchets on the opposite sides thereof and a pivoted lever adapted to engage with one of said ratchets 20 when moved in one direction, of a stop-catch adapted to limit the movement of said operating-gear, said stop-catch being normally held out of its engaging position by a cam on said lever, said cam being adapted to release 25 said stop-catch before said lever reaches the limit of its forward stroke, a crank-gear engaging with said operating-gear, and means, substantially as described, for connecting said crank-gear to the dropping mechanism, 30 substantially as specified.

6. The combination, in a check-rower and with the supporting-frame thereof, having a projecting lug or ear provided with an elongated opening and horizontal serrations 35 therein, of a fastening-plate having the annu-

lar wings, as described, one of which is provided with serrations corresponding to the serrations on said projecting ear, and the other wing being adapted to be secured to the planter-frame, substantially as specified.

40

7. The combination, with the operating-lever, of the operating-gear having oppositely-arranged ratchets on opposite sides thereof and adapted to be moved in one direction by the vibration of said lever engaging with one 45 of said ratchets, a crank-gear engaging with said operating-gear, and an adjustable two-part link connection from said crank-gear to the dropping mechanism, substantially as specified.

50

8. The combination, with the main frame, of an operating-gear having oppositely-arranged ratchet-teeth on the opposite sides thereof, said gear being adapted to turn on a sleeve secured to the main frame, a crank- 55 gear journaled in a bearing on said frame and adapted to mesh with said operating-gear, an adjustable crank-arm secured to said crank-gear, a bolt extending through said gear and crank and adapted to hold said 60 parts in their relative positions, and a collar through which said bolt passes, adapted to hold said gear in its bearings, substantially as specified.

In testimony whereof I have hereunto set 65 my hand this 2d day of May, A. D. 1890.

AUSTIN C. EVANS.
